UNITED STATES PATENT OFFICE.

FAY A. PYLE AND CLAUDE E. MELTON, OF SCOTTSBLUFF, NEBRASKA.

BOILER-FEED REGULATOR.

Application filed October 24, 1924. Serial No. 745,665.

To all whom it may concern:

Be it known that we, FAY A. PYLE and CLAUDE E. MELTON, citizens of the United States, residing at Scottsbluff, in the county 5 of Scotts Bluff and State of Nebraska, have invented certain new and useful Improvements in Boiler-Feed Regulators, of which the following is a specification.

This invention relates to a boiler feed 10 regulator and has for its object to provide, in a manner as hereinafter set forth, means for controlling the operation of a feed pump to regulate the supply of water to a steam boiler.

15 Further objects of the invention are to provide, in a manner as hereinafter set forth, a boiler feed regulator, which is simple in its construction and arrangement, strong, durable, automatic in its action, 20 thoroughly efficient and convenient in its use, readily installed, and comparatively inexpensive to set up.

With the foregoing and other objects in view, the invention consists of the novel construction, combination and arrangement of parts, as hereinafter more specifically described and illustrated in the accompanying drawings, wherein is shown an embodiment 25 of the invention, but it is to be understood that changes, variations and modifications can be resorted to which come within the scope of the claim hereunto appended.

30 In the drawings wherein like reference characters denote corresponding parts throughout the several views:—

Figure 1 is a side elevation of a boiler feed regulator, in accordance with this invention.

Figure 2 is a top plan view.

40 Figure 3 is a fragmentary view in cross section.

Figure 4 is a side elevation illustrating the regulator in operative position during the feed to the boiler.

45 Referring to the drawings in detail, 1 denotes a support provided with a resilient abutment 2, which extends upwardly therefrom as well as being arranged at one end thereof. The other end of the support 1 is 50 provided with a vertically disposed stop member 3 of greater height than the abutment 2. The upper face of the abutment 2 is bevelled, as at 4. The support 1, at a point between the abutment 2 and stop 3, is 55 formed with a vertically disposed yoke 5

and between the latter and the stop 3 with an opening 6.

Arranged above the support 1 is a water receiving tank 7, which is eccentrically pivoted. Depending from the bottom of the 60 tank 7, near one end thereof, is an arm 8, which extends within the yoke 5 and is pivotally connected thereto, as at 9.

Leading from a source of water supply, 65 which can be a tank containing accumulated condensate from a heating system, is a feed pipe 10 provided with a controlling valve 11. Communicating with the pivoted end of the tank 7 is a flexible pipe branch 12, which is connected to the lower end of the 70 feed pipe 10, by an elbow coupling 13. When the valve 11 is opened the water will be fed to the tank 7. The flexible pipe branch 12 opens into the tank 7 at the top thereof. Communicating with the pivoted 75 end of the tank 7, near the bottom thereof, is a flexible pipe branch 14, which is connected by an elbow coupling 15 to a water line 16, which opens into the feed pump, not shown. The flexible pipe branch 12 constitutes an inlet for the tank 7, and the flexible pipe branch 14 provides an outlet for the 80 tank 7.

Secured to the top of the tank 7, centrally 85 thereof, through the medium of the hold-fast devices 17, is a longitudinally extending rod 18, which projects from that end of the tank 7 to which the branches 12 and 14 are secured. The rod 18 carries a counter-weight 19, which is adapted to engage the 90 stop 3 for limiting the pivoting movement in one direction of the tank 7 and further to normally maintain said tank in position as shown in Figure 1. The counter-weight 19 is connected to the free end of the rod 18 95 by the hold-fast device 20.

Secured to one side of the tank 7, at that end to which is connected the pipe branches 12 and 14, is a vertically disposed bar 21, which extends above and depends below the 100 tank 7. Hold-fast devices 22 are employed to fixedly secure the bar 21 in position. Leading to the feed pump, not shown, is a normally closed steam line 23 therefor. The steam line 23 has interposed therein a valve 105 24 having the outer end of its stem 25 provided with a shifting member 26 therefor. The member 26 is formed with a pair of oppositely extending arms 27, 28. Pivots 110 connected to the arm 27, as at 29, is one end

of an actuating rod 30 for the member 26. The connection 29 provides for lost motion. The rod 30 has its other end pivotally connected, as at 31, to the upper end of the 5 bar 21. Pivotally connected, as at 32, to the arm 28 is one end of the actuating rod 33 for the member 26. The connection 32 provides for lost motion. The other end of the actuating rod 33 is pivotally connected, as 10 at 34, to the lower end of the bar 21.

When the elements of the device are in the position as shown in Figure 1, the steam line 23 is closed and the feed pump, not shown, is not operating. When the device 15 is in operation, water is continuously supplied through pipe 10 to tank 7, but the flow is regulated through the medium of the valve 11. If the water is fed to the tank 7, the weight of the water overcoming the 20 counter-weight 19 will cause the tank to assume the position as shown in Figure 4. As the tank 7 moves to the position shown in Figure 4, the actuating rod 30 will open the valve 24, whereby steam will be supplied by 25 the line 23 to the pump to cause the operation thereon, and on the operation of the pump the water will be supplied to the boiler. As the water is removed from the tank 7, due to the action of the pump, the counter-weight will restore the tank to the 30 position shown in Figures 1 and 3, and as the tank moves to such position the actuating rods 30 and 33 will close the valve 24, thereby shutting off the supply of steam through 35 the line 23 and cause the discontinuance of the operation of the pump.

When the head in the tank containing the accumulated condensate is greater than usual, more frequent actuation of the tank 7 results, 40 together with more frequent feeding of the boiler through the pump. Similarly, when the head is not as great as usual, less frequent actuation, and consequently less frequent feeding, is accomplished. This 45 effects a feeding of the accumulated condensate which is approximately proportional

to the steam taken by and condensed in the system.

It is thought that the many advantages of a boiler feed regulator, in accordance 50 with this invention can be readily understood, and although the preferred embodiment of the invention is as shown and described, yet it is to be understood that changes in the details of construction can be 55 had which will fall within the scope of the invention as claimed.

What we claim is:—

A regulator for the purpose set forth comprising a support, a water receiving tank 60 arranged thereover, spaced therefrom and having one end pivotally connected therewith, an arm extended from the top of the pivoted end of the tank and having connected to its outer end a depending counter-balancing weight for maintaining the tank in normal or balanced position with respect to the support, a bar fixed to one side of the tank, means for supplying water to the tank to shift the latter from balanced position, a 70 water discharge pipe for the tank leading to a pump, a pump steam line valve shifting member, means carried by the lower end of the bar and having a lost motion connection with said member for maintaining the 75 valve of the steam line to the pump closed when the tank is in normal position, means carried by the upper end of the bar and having a lost motion connection with said member for opening the valve in said steam line 80 when the tank is shifted from normal position, a stop carried by said support for limiting the movement of said counter-balancing weight when the tank shifts to normal position, and a beveled resilient abutment 85 carried by the support, of less height than the stop, and engageable by the tank when the latter is shifted from normal position.

In testimony whereof, we affix our signatures hereto.

FAY A. PYLE.
CLAUDE E. MELTON.
